UNITED STATES PATENT OFFICE.

WILLIAM EMIL BOCK, OF TOLEDO, OHIO, ASSIGNOR TO THE TOLEDO GLASS COMPANY, OF TOLEDO, OHIO, A CORPORATION OF OHIO.

FIRE-FINISHING MACHINE.

SPECIFICATION forming part of Letters Patent No. 761,139, dated May 31, 1904.

Application filed May 20, 1902. Serial No. 108,246. (No model.)

To all whom it may concern:

Be it known that I, WILLIAM EMIL BOCK, a citizen of the United States, residing at Toledo, in the county of Lucas and State of Ohio, 5 have invented certain new and useful Improvements in Fire-Finishing Machines, of which the following is a specification, reference being had therein to the accompanying drawings.

The invention relates to machines for finishing articles of glassware, the machine herein shown comprising a rotary holder for the article, having means for exhausting the air from beneath the article to hold it thereon by atmospheric pressure, which I herein refer to as 15 a "suction-arm."

The invention relates to the means for controlling the air-exhausting devices, the drive mechanism for the suction-arms, and the construction, combination, and arrangement of 20 the various parts, all as more fully hereinafter described, and particularly pointed out in the claims.

In the drawings, Figure 1 is a vertical central section through one-half of the machine, 25 showing a suction-arm with the article thereon and the mold or former in operative position to the article, the other parts being shown in corresponding position. Fig. 2 is a perspective view of one of the suction-arms with the 30 mold or former in its operative position and with the temporary rest or support upon which the article is placed beside the suction-head in position to receive the tumbler and in perspective view the glow-box or burner 35 through which the article is to be passed.

Fig. 3 is a diagram elevation of the suction-arm, the temporary rest, and the means for moving the suction-arm to couple it with the exhaustmechanism, showing in full and dotted 40 lines different positions thereof. Fig. 4 is a similar diagram elevation of the same parts, showing the temporary rest and the pushing-finger disengaged from the tumbler and being withdrawn therefrom. Fig. 5 is an elevation 45 of the suction-arm and its connected parts, showing the article in the glow-box and the mold or former being wet and cooled in the tank. Fig. 6 is an enlarged section through the suction-head. Fig. 7 is a plan view of

the machine, illustrating the arrangement of 50 the suction-arms, the glow-boxes or burners, and the drive connections, many of the parts being omitted for the purpose of illustrating these features. Fig. 8 is a side elevation of the drive connection for the machine and the 55 suction-arms.

The machine is supported upon any suitable base, to which is secured the post A, upon which the operating parts turn.

B is the rotary frame, journaled on the post 60 A and carrying the operating parts. On the lower end of the tubular portion of the frame B is secured a worm-gear 1, with which a worm 2 on the shaft 3 engages for rotating the frame. This shaft 3 is driven from any 65 suitable source of power. In this case I have shown it driven from a shaft 4, driven by a motor 5. This same shaft 4 may be provided with suitable cranks or eccentrics 6 for driving the exhaust-pump 7, which connects with the 70 central port *a* through the post A and by the cross-port *b* connects with the annular exhaust-chamber *c*, formed around the post A and within the tubular part of the frame B.

The frame B is provided with a series of radial arms C, on each of which in suitable journals D are supported the suction-arms E. These suction-arms are shown in the form of hollow spindles or shafts, the inner ends extending into or connecting with the vacuum-chamber *c*. I have shown a bushing *d*, forming the journal for the inner end of the shaft and projecting into the vacuum-chamber, provided with ports *e*, with which are adapted to be registered the cross-ports *h* near the end of 85 the suction-arms.

i is an air-inlet port, preferably controlled by the valve *k*, operated by the crank-arm *l*, which in turn is actuated by the roller-wrist *m*, actuated by the cam *n* (secured by the 90 bracket *n'* to the post A) in one direction and by the link *o*, connecting with a collar *r* on the suction-arm E. The suction-arm is rotated by a bevel gear-wheel 9, having a spline engagement with the suction-arm, so that the 95 latter may move endwise therethrough and yet be driven thereby. The bevel gear-wheel 9 meshes with the bevel gear-wheel 10 on the

vertical shaft 11, journaled in brackets 12 on the frame B.

Upon the lower portion of the shaft 11 are the two gear-wheels 13 and 14, loose upon the shaft and adapted to be connected therewith by means of the clutch 15, which is actuated by the lever 16, having a roller at its outer end engaging the cam 17, secured to the standards 18, which rise from the base. The gear-wheel 13 is in mesh with an annular gear 19 on the sleeve 20, which is journaled upon the lower tubular portion of the frame B, as plainly shown in Fig. 1.

21 is an annular gear upon the sleeve 22, journaled upon the outer face of the sleeve 20. The sleeve 22 is provided at its lower end with a bevel-gear 23, which is driven by a bevel-pinion 24 on the shaft 4. Upon the shaft 4 is another bevel-pinion, 25, which meshes with the bevel gear-wheel 26 on the vertical shaft 27, journaled in the vertical bearing 28 on the base of the machine. The shaft 27 is provided with a gear 29, which meshes with a spur-gear 30 upon the lower end of the sleeve 20. These parts are so arranged that when through the medium of the cam 17 and the lever 16 the gear-wheel 13 is coupled to the shaft 11 the suction-arm E will be driven at a comparatively slow speed—say thirty revolutions a minute; but when through the action of the cam 17 the gear-wheel 14 is coupled to the shaft 11 then the suction-arm E will be driven at a high speed—say three hundred revolutions a minute. There is sufficient space between the gear-wheels 13 and 14 so that the clutch-collar 15 may be arrested intermediate the two and in which position the rotation of the suction-arm will entirely cease. It is evident that the cam 17 may be arranged, without further illustration of it, so as to effect these movements at the desired time in the rotation of the frame.

Referring to Fig. 2, 35 is a temporary rest-support or table upon which the operator may place the tumbler or other article to be fire-finished, this rest being of such a shape and arranged in such relation to the head 36 on the end of the suction-arm as to properly center the article thereon, so that its axis will be exactly the axis of the rotating suction-arm. If the article were placed eccentrically upon the suction-head, the rotation of the same would distort it after it became heated, and therefore it is quite essential that the article should be placed properly upon the suction-head to prevent this difficulty. The rest 35 I have shown as semicircular in shape, slightly tapering to receive the ordinary tumbler, and it is detachably supported in the outer end of a slide 37. The slide is provided with the vertical posts or studs 38, adapted to engage between the flanges 39 of the rest 35, so that different rests may be inserted for tumblers of different size or shape. The parts are shown in Fig. 2 in position to re-

ceive the article from the operator. The slide 37 moves in horizontal guides in the radial arms C and is moved in and out by the engagement of the roller-wrist 40, Figs. 1, 3, and 4, in a cam-groove 41, formed on the top 70 of the posts 18. Fig. 3 shows the tumbler 45 in position upon the rest. As soon as the tumbler is laid thereon, the rotation of the frame B continuing, the cam 41 starts to retract the rest to the position shown in Fig. 1, 75 and such inward movement causes the finger 46 on the lever 47, pivoted on the slide 37, to engage the outer edge of the tumbler, as shown in Fig. 3, and to move the tumbler against the outer face of the suction-head 36. The further inward movement of the slide will move the tumbler longitudinally and likewise move the suction-arm inward. In the initial position shown in Fig. 3 the cross-port h in the end of the suction-arm is in alignment with 80 the air-inlet port i and the passage through the arm is in communication with the atmosphere. The continued inward movement of the suction-arm thus pushed by the finger 46 will move the port h away from the air-inlet 85 port i and into the vacuum-chamber c, as shown in Fig. 4. As soon as this occurs the air in the suction-arm will be exhausted, and by means of the annular port 51 in the suction-head the air beneath the tumbler or a part thereof will be exhausted, and the article will be held upon the head by the "suction" or the atmospheric pressure. The finger 46 is held up in engagement with the tumbler during this operation by reason of the engagement of the inner arm 52 of the lever 47 beneath the cam 53, formed on the arm C, previously described. As soon as the suction-arm has been moved inward, so that its passage is connected with the vacuum-chamber, 90 the finger will drop down and disengage from the edge of the tumbler because of the disengagement of the arm 52 from the cam 53, the parts then being in the position shown in Fig. 4. The rest 35 will be drawn in beyond the 95 head and into the position shown in Fig. 1, so as to be clear from the tumbler and fire-finishing and forming operations.

The suction-head is illustrated in detail in Fig. 6, and in this case consists of a sleeve 54, 100 screwed onto the end of the suction-arm, provided with an annular flange 55, within which is fitted the block 56, leaving between the flange and the block an exhaust-port 51, connected with the passage through the suction-arm by the ports 58 and the passage 59. The block 56 is of suitable shape to fit in the concave bottom of the tumbler, while the flange 55 will receive the end of the rim thereof, thus supporting the tumbler by its bottom face 105 only, the support being of such a shape as to prevent the distortion thereof by the atmospheric pressure thereon. By means of this construction I can do away with the guides or receptacles which grasp or inclose the exte- 110

115

120

125

130

rior of the article, so that I am able to finish the entire exterior surface to eliminate all mold-marks on pressed ware, and am also enabled to support the article without marking or marking the bottom face in any way. During this period in the travel of the suction-arm when the article is being attached thereto the drive mechanism is preferably disconnected from the suction-arm, the clutch 15 being in the intermediate position referred to. As soon as the article is attached the clutch 15 is thrown into engagement with the gear-wheel 13, and the suction-arm, with its article, is rotated at the slow speed. The article may be applied to the suction-arm at about the point lettered G in Fig. 7, the suction-arm traveling in a direction indicated by the arrow. The traveling of the suction-arm rotating at slow speed, as before described, will bring it into the glow-box 60. (Illustrated in Figs. 2, 5, and 7.) This glow-box is segmental in shape, being lined with fire-clay 61 and having a fire-chamber 62 therein, being open at the ends to admit the article and having a slot 63 in the front face to permit of the passage therethrough of the suction-arms or spindles. This slot may be closed by means of the segmental plates 64, carried by the revolving frame B and extending between the outer ends of the suction-arms, as plainly shown in Figs. 2 and 7. This is simply to prevent the loss of heat from the glow-box in the space between the suction-arms. The glow-box is fed with gas and air, preferably by a suitable inlet-pipe 66, entering through the top at or near the middle thereof. During the travel through the glow-box the fire-finishing process is completed, the sharp corners of the edges being melted and the exterior being softened, so as to eliminate any mold-marks that may be thereon. The article is rotated during its passage through the glow-box at the slow speed referred to. While I have shown and prefer to use a glow-box adapted to receive the entire article, the shape of the glow-box and its action upon the article may be varied to suit the various requirements of the articles to be fire-finished. For instance, in blown tumblers, if desired, the edges alone might be presented to the heat instead of, as shown in these drawings, the entire article being in the flame-chamber. When the article leaves the glow-box 60, the glass is heated to such a condition that it is slightly plastic or malleable—that is, so it might be bent slightly by pressure applied to it. The necessity for having the axis of the article in line with the axis of the suction-arm is quite obvious when the glass is in this condition, this having been fully explained heretofore. The article is now given its final shape and its exterior polish by means of the mold or form 75, secured to the arm 76, pivoted at 77 in the outer end of one of the arms C beneath the suction-arm. On the pivot-

pin 77 of the arm 76 is a gear-segment 78 in mesh with a rack 79, sliding in guides on the under side of the arm G, Fig. 1. This rack 79 is provided with a roller-wrist 80, engaging a cam 81, carried by the posts 18. The cam is of such shape that just as the article leaves the glow-box 60 the rack will be moved outward, rocking the arm 76 upon its pivot and lifting the mold or form into engagement with the under side of the glass article. Just before or at the time that the mold or form engages the glass article the clutch 15 will be shifted by the cam 17 into engagement with the gear-wheel 14, imparting the high speed to the suction-arm, so that the article will be rotated as soon as the former engages therewith at a sufficiently high speed to throw the semiplastic glass into contact with the former or mold and give it a perfect shape, at the same time polishing it by its rotation against the mold-surface. The engagement of the mold or form with the article takes place at about the point H, Fig. 7, and continues around to about the point J. At about the point J in its travel the mold or former is disengaged from the article by an inward movement of the rack 79, and at the same time the cam n, engaging the roller-wrist m, will actuate the lever l, the link o, and by the engagement of the link o with the collar r will shift the suction-arm outwardly, withdrawing the port e from the vacuum-chamber c and causing it to register with the air-port i, the air-valve k being opened by the same movement. This will destroy the vacuum in the suction-arm, restoring atmospheric pressure therein, and the tumbler will fall off, being received either by the operator or upon a suitable guideway or receptacle. (Not shown.) At some suitable point in its travel the mold or former is preferably cooled and wet. To accomplish this, I have shown a tank 82 arranged beneath the glow-boxes, and the cam 81 is so shaped that as the former reaches the edge of the tank it will be lowered, as shown in Fig. 5, traveling through the water until it is ready to be applied to the article just beyond the glow-box 60, when it will be lifted into operative engagement with the article, as before described.

The form 75 is supported in a chair 83 upon the outer end of the lever 76 and is adjustable by means of the set-screws 84, so as to fit it perfectly to the article, and when adjusted it may be clamped in position by the winged nut 85. This mold is not only therefore adjustable, but detachable, so that molds of different shapes and sizes of articles may be applied and adjusted accurately to the article to be polished.

I will now briefly state the operations of the machine as a whole. Motion being imparted to the frame B around its post or pivot A, the operator lays an article upon the rest 35, which centers it in relation to the suction-

head, and by the mechanism described the air is exhausted from beneath the article, thereby connecting it to and holding it tightly on the seat. The rest is then withdrawn from beneath the head. The article then passes through the glow-box, being rotated at slow speed, during which time the mold is being wet and cooled in the tank. As soon as the article is fire-finished in the glow-box and emerges therefrom the mold or form is moved into contact therewith, and the article is rotated at high speed, polishing and shaping it in the mold. When shaped and polished, the mold is withdrawn, atmospheric pressure is restored in the suction-arm, and the article drops away from its seat.

I have described the operation of but a single arm; but, as is plain from the drawings, a number of these arms may be carried by the frame B, in this case eight being shown, and moved successively through the operations described.

In case no article is placed upon the rest when it arrives at the proper point to receive an article then the finger 46 will not impinge upon anything, and therefore the suction-arm will not be shifted longitudinally and will not be connected with the vacuum-chamber. Thus the suction-arm is rendered operative only by the placing of the article on the suction-arm, and the suction-arm is connected with the vacuum-chamber by and upon the application of the article.

I consider it quite desirable to have the arms E arranged in a horizontal position, for the reason that when they are arranged vertically gravity will act to elongate or shorten the article when it is in its plastic condition. In the horizontal position the tendency of gravity does not tend to elongate or shorten it, but only to distort the article laterally, and this is overcome by revolving it. I do not, however, desire to limit myself to the use of the suction-arm or the other devices in horizontal position, although I deem that the preferable arrangement.

What I claim as my invention is—

1. The combination of a movable suction-arm rotatable about its longitudinal axis, of means for exhausting the air therefrom operable through and upon the application of the article thereto, said article being rotatable with the suction-arm.

2. The combination of a movable suction-arm rotatable about its longitudinal axis, of automatic means for exhausting the air therefrom operable upon the application of the article thereto, said article being rotatable with the suction-arm.

3. The combination of a movable suction-arm rotatable about its longitudinal axis, an air-exhaust device connected therewith, and means for controlling the production of the vacuum beneath the article operable only upon

the application of the article thereto, said article being rotatable with the suction-arm.

4. The combination of a fire-finishing furnace, a rotary suction-head, means for successively exhausting the air therefrom, for moving the head in operative relation to the fire-finishing furnace, for cutting off the exhaust connection and admitting air therein.

5. The combination of a rotary suction-head, means for successively exhausting the air therefrom, for moving the head in operative relation to a fire-finishing furnace for moving a shaping-mold into operative relation thereto, rapidly rotating the head while the mold is thus arranged, and for cutting off the exhaust connection and admitting the air therein.

6. In a fire-finishing machine, the combination of a traveling suction-head, means for rotating the head about its longitudinal axis, and means for exhausting the air therefrom to hold an article thereon, operable only upon the application of the article thereto and for restoring the air to said head for detaching the article therefrom.

7. In a fire-finishing machine the following instrumentalities traveling together and co-operating for the purpose described, a rotating head, a movable support for the glass article, adapted to be moved away from the head after the article is connected thereto, and a shaping-mold movable into and from operative relation to the head.

8. In a fire-finishing machine, the following devices movable together and co-operating for the purposes described, a rotary suction-head, means for creating a partial vacuum and restoring the air-pressure therein, a support for the article adjacent to the head, movable into and from operative relation to the head, and a shaping-mold likewise movable into and from operative relation to the head, combined with mechanism for rotating the head and operating the support and mold.

9. The combination of a suction-arm rotatable about its longitudinal axis, means for automatically exhausting the air therefrom operable by and only upon the application of the article thereto, and a rotatable support for the rotary suction-arm.

10. The combination of a movable suction-arm rotatable about its longitudinal axis, means for automatically exhausting the air therefrom operable only by and upon the application of the article thereto, said article being rotatable with the suction-arm.

11. The combination of a support for a glass article, a suction-arm adjacent thereto, means for exhausting the air therefrom by and upon the application of the article thereto, and for admitting atmospheric pressure thereto to disconnect the article, and means whereby the support may be moved into and from operative relation to the suction-arm.

12. The combination of a fire-finishing furnace or burner, a rotating suction-head movable to carry an article thereon, in and out of the same, and means for connecting an exhausting device to the head before approaching the furnace, and for admitting atmospheric pressure to the head on leaving the furnace.

13. The combination of a fire-finishing furnace or burner, a rotating suction-head, with a relative movement therebetween to carry the article into and out of the furnace, and means for exhausting the air from the head while the article is in the furnace, and for admitting atmospheric pressure thereto to disconnect it therefrom.

14. The combination with a suction-arm rotatable about its longitudinal axis, of means

for automatically exhausting the air therefrom, operable only upon the application of 20 the article thereto.

15. The combination with a fire-finishing furnace, of a suction-head rotatable about its longitudinal axis, means for exhausting the air from the suction-head, means for moving 25 the head into operative relation to the fire-finishing furnace, and means for cutting off the exhaust connection, and admitting air into the head.

In testimony whereof I affix my signature in 30 presence of two witnesses.

WILLIAM EMIL BOCK.
